FABRIC-SUPPORTING MEANS FOR
CIRCULAR LOOMS

Joanny Jabouley, Spandon, near Derby, England,
assignor to Celanese Corporation of America,
a corporation of Delaware

Application January 12, 1934, Serial No. 706,323
In Great Britain January 24, 1933

4 Claims. (Cl. 139—13)

This invention relates to circular looms, its principal object being to ensure even disposition of the warp threads within the fabric.

In circular weaving a relative motion between the weft inserting means and the warps results in a tendency for the warps to be dragged round into an inclined position, with the result that they tend to assume a similar position in the fabric. Further, this tendency for dragging extends into the fabric itself, until a balance is reached between the turning force applied to the warps and the resistance of the warps to turning. A major result of this turning of the warp is that it causes the warps to assume an uneven spacing, or prevents the warps regaining their even spacing if this has been upset by any other cause. Moreover, it is not convenient to employ a reed in a circular loom to space the warps evenly at each pick, as in ordinary looms, so that the above-mentioned tendency results in uneven fabric.

According to the present invention dragging round of the fabric is prevented by carrying the fabric over a cylindrical supporting ring which extends to the fell of the fabric, the outer surface of said ring being covered with fabric, felt, or the like, so that there is a firm gripping between the fabric being woven and the surface of this ring on the contraction of the fabric under the weaving tension on to the rough surface of the ring.

In order to maintain sufficient grip the ring should be of considerable length; further, in order to ensure that this gripping is maintained even where the fabric is of a somewhat extensible character, whether by reason of low pick density and/or warp spacing, or by the character of the yarns employed, a member may be employed to embrace the fabric immediately after it has passed the ring so as to contract it, and by exerting tension at this point to draw the fabric firmly against the ring.

The invention will now be described in greater detail with reference to the accompanying drawing, in which

Fig. 1 is a partial view of a loom in vertical section;

Fig. 2 is a plan view of a detail shown in Fig. 1; and

Fig. 3 shows in side elevation the rollers of the take-up mechanism.

Fig. 1 shows warp threads 3 proceeding downwards from warp beams (not shown) through a reed 4 carried by a ring 5 mounted on a central vertical shaft 6. Below the reed 4 are the shut-

ting 7, these being positioned between the warp sheets by the means described in U. S. application S. No. 706,322 filed on even date herewith. The positioning means comprise rotatable vane wheels 8 located outside the warp circle and passing through the outer sheet of warps to engage rollers 9 mounted for free rotation in the shuttle body, and a roller 10 freely mounted in the shuttle body to run against the face of a ring 11 carried by the shaft 6.

The shuttle 7 extends downwardly as far as the top of a fabric-supporting ring 12 carried by the shaft 6, weft delivered from the spool 13 in the shuttle being pressed by the shuttle into the fell of the fabric 14 at the upper edge of the ring 12. The ring 12 is covered with a layer of fabric 15 so that the fabric being woven is firmly gripped as it proceeds downwards over the face of the ring 12.

Assuming the diameter of the ring 12 to be 1 metre, the depth of the ring shown in the drawing is 150 mm. The depth, however, may be greater than this, for example 200 or 250 mm. With looms of other diameters, appropriate depths are given to the ring 12.

Under the tension imparted to the weft at the fell of the fabric and the pressure exerted by the shuttles in forcing the weft between the warps, the fabric tends to contract somewhat, and thus grips the fabric covering 15 firmly. In this way, a strong resistance is set up against the tendency of the warps to displacement due to the relative movement between the shuttles and warps. The warps are therefore enabled to maintain their spacing.

In order to ensure that the gripping of the fabric by the ring 12 is maintained even where the fabric is of a somewhat extensible character whether by reason of low pick density and/or warp spacing or by the character of the yarns employed, a ring 16 is arranged to surround the fabric just below the ring 12 so as to contract the fabric and by exerting tension at this point to draw the fabric firmly against the ring 12. Preferably the ring 16 is provided with means such as the nut and bolt arrangement 17 shown in Fig. 2 to enable it to be drawn or pressed into engagement with the fabric with a force in accordance with the nature of the fabric. For ease of assembly the ring 16 may be made in two or more sections, the nut and bolt arrangement 17 serving to connect the sections together as well as to adjust the pressure required to be exerted by the ring to contract the fabric.

Where the warps 3 rotate, the ring 12 is driven

by the shaft 6 to rotate at the same rate. The ring 16 is likewise mounted on a member 18 rotating with the warps, the ring being supported by any suitable number of link connections 19. 5 Where the warps are stationary, the rings 12 and 16 are also held stationary.

Used in conjunction with means to cause the warps to vibrate at the point where they enter the fabric, as described in U. S. application S. No. 655,559 filed 7th February, 1933, the invention enables very even spacing of the warps to be obtained notwithstanding the absence of reed-like spacing means operating at beat-up as is found necessary in ordinary weaving practice. 10

15 Below the ring 16 the tubular fabric 14 spreads outwardly to reach the sand-roll 20 of a take-up device in doubled form. A spreading arm 21 inside the tube of fabric engages the fold of the fabric just in advance of the roller 20 to enable 20 the fabric to be collected without creases or folds across its width. The arm 21 is pivotally mounted at 22 upon a bracket 23 carried by the shaft 6, a screw 24 threaded through an extension 25 of the bracket 23 engaging the upper end 26 of the 25 arm 21 to enable the lower end of the arm to be pressed outwardly against the fold of the fabric at any desired pressure. The screw 24, being near the fell of the fabric, can be easily reached through the warps 3 for adjustment of the arm 21. A similar arm 21 (not shown) is mounted on the bracket 23 on the other side of the shaft 6 to engage the similar fold at the other side of the tubular fabric.

From the roller 20, the doubled fabric 14 passes 30 over and under the gripping rollers 27, 28, the roller 28 running in a slot 29 so as to press by its weight against the roller 27. Tension is maintained on the fabric by the rollers 20, 27, 28 even if the take-up roller 30 is run back or even removed for unwinding of fabric, and consequently the pressure of the fabric on the ring 12 (which depends, of course, on the tension imparted by the take-up device) remains unaffected during 40 removal of fabric.

45 Rollers 31 are mounted outside the ring 12 to guide the ring by pressure through the fabric. The rollers 31 are carried by a cranked bracket 32 mounted on a ring 33 which supports the

brackets 34 for the shafts 35 on which the vane-wheels 8 are secured. Free rolling movement between the ring 12 and the rollers 31 is thus secured. Preferably a second roller 36 is associated with each roller 31, the roller 36 rolling against the inner face of the ring 12 to ensure the accurate centering of the ring 12. 5

The brackets 32 and the rollers 31 are depressed below the upper edge of the ring 12, thus making the fell of the fabric accessible and facilitating the tying-in of broken warp ends.

What I claim and desire to secure by Letters Patent is:—

1. In a circular loom, a cylindrical fabric-supporting ring extending downwardly from the fell of the fabric being woven, said ring being covered with material adapted to grip the fabric, a member adapted to embrace the fabric below the supporting ring, and means to contract said member about the fabric to draw the fabric firmly against the ring. 15

2. In a circular loom, a deep cylindrical fabric-supporting ring extending to the fell of the fabric being woven, a cover for said ring having a rough surface adapted by gripping the fabric to resist slipping of the fabric circumferentially of the ring, and a member disposed near said ring and adapted to embrace the fabric on the side of the ring remote from the fell of the fabric so as to assist the gripping of the fabric by said cover. 30

3. In a circular loom, a cylindrical fabric-supporting ring extending to the fell of the fabric being woven, a fabric covering over the outer surface of said ring, said fabric covering being adapted to grip the fabric and to resist any tendency to relative circumferential motion between said ring and said fabric during the weaving operation. 35

4. In a circular loom, a cylindrical fabric-supporting ring extending to the fell of the fabric being woven, a cover for said ring formed from a material having a high coefficient of friction and adapted by gripping the fabric to resist any tendency to relative circumferential motion between said ring and said fabric during the weaving operation. 40
